SHAKING SCREEN

William Louis Wettlaufer, Buffalo, N. Y., assignor
to The W. S. Tyler Company, Cleveland, Ohio,
a corporation of Ohio

Application April 30, 1932, Serial No. 608,436

1 Claim. (Cl. 209—326)

This invention relates to screening machines and particularly to a vibrating screen of the gyratory type designed for fine as well as coarse screening operations.

5 One of its objects is the provision of a positively gyrated and balanced screening machine which transmits the vibrations to all points of the screen surface yet avoids destructive vibration of the machine or building, which is driven 10 at high speeds, and which not only produces a very efficient separation of the plus and minus materials but effectually maintains the screen meshes open at all times.

Another object of the invention is to provide 15 a heavy duty screening machine of this character which has been designed for maximum production and which is provided with simple and effective means for yieldingly resisting movement of the live screen body out of its normally balanced 20 state and for maintaining the same in correct screening position and without affecting the positive gyration thereof.

In the accompanying drawings:—Figure 1 is a perspective view of a screening machine embodying my invention. Figure 2 is a side elevation thereof. Figure 3 is an enlarged fragmentary cross section thereof taken on line 3—3, Figure 2. Figure 4 is a similar view taken on line 4—4, Figure 2.

30 Similar characters of reference indicate corresponding parts throughout the several views.

The screen body or live screen frame of the machine may be of any suitable and well known construction, that shown in the drawings, by way 35 of example, consisting of side plates 10, 10 carrying upper and lower screening surfaces or decks 11 and 12 of coarse and fine mesh, respectively, the whole being supported for rotating or gyrating motion upon a suitable frame structure 13 which may be of any appropriate design. In 40 practice, this supporting frame and the live screen frame carried thereby are usually disposed in a more or less inclined position, as shown in Figure 2.

45 The live screen frame, as a whole, is balanced or supported for rotating vibratory movement midway of its ends by a rotary transverse shaft 14 journaled at its ends in suitable bearings 15 supported on the main frame 13 and extending 50 through the side walls 10 of the live frame at substantially its center of gravity. The shaft-bearing shown in Figure 3 of the drawings is of the heavy duty roller bearing type embodying the self-aligning feature and effectually sealed to exclude 55 grit and foreign matter by labyrinth seals.

This shaft constitutes the drive shaft for the machine and imparts to the live frame a positive, circular or gyrating movement whereby all points of the screening surface are vibrated in a circular path or orbit and to this end said shaft has offset 5 or eccentric portions 16 on which the live frame is supported, the latter having roller bearings 17 attached to the side walls or plates 10, 10 therefore in which the eccentric shaft portions are journaled.

10 For the purpose of maintaining the machine in proper balance, I provide counter-balance wheels 18, 18 which are mounted on the eccentric shaft 14 preferably between the bearings 15 and 17 and which are provided with radially-adjustable weights 19 held in a set position by bolts 20. Applied to one end of the drive shaft is a pulley 21 which may be connected by a belt to an electric motor or other source of power.

15 In the heavy duty type of screening apparatus to which this invention relates, it is built in widths varying from four to six feet and in lengths from eight to fourteen feet, and it is therefore necessary to employ resilient means 20 acting upon the opposite ends of the live screen frame for yieldingly resisting movement thereof 25 out of its normally balanced state and for maintaining such live frame in proper screening position irrespective of the load distribution there-over and without in any way disturbing or interfering 30 with the positive gyratory movement transmitted to the live frame by the shaft 14. For this purpose, the fore and aft portions of 35 this live frame are preferably suspended over or supported upon a plurality of yieldable elements which may be in the form of compression springs 22 disposed in longitudinal rows at opposite sides of the shaft-axis, the several springs being of substantially the same size or capacity. As shown in Figures 1, 2 and 4, these springs are 40 arranged in suitable housings 23 secured to the outer sides of the plates 10 and are seated at their lower ends on supporting bars 24 secured to the main frame 13 of the machine, the springs being disposed in a substantially upright position 45 between these parts to yieldingly sustain the ends of the live frame. By this arrangement, it will be noted that the springs are disposed at different distances from the shaft-axis and in substantially horizontal alignment, with the result 50 that the action of the several springs is uniformly distributed at different points lengthwise of the screen in such a manner that the sensitivity of the live frame is not affected at any point nor is its balance disturbed or interfered with,

thereby affording the same uniform circular motion of the live frame from one end thereof to the other in these heavy duty machines. The upper or active ends of these springs with respect to the live frame are preferably disposed along a line substantially intersecting the axis of the drive shaft 14 and parallel to the screen surfaces of such frame, as seen in Figure 2, whereby the setting up of disturbing forces is effectually eliminated and the circular vibrating action of the live frame is positively maintained over its entire area.

I claim as my invention:—

The combination of a live screen frame, a stationary frame, a rotary supporting shaft for said live frame arranged substantially centrally and transversely thereof for balancing it and journaled at its ends in said stationary frame,

connections between said shaft and live frame for positively gyrating the latter in circular paths, means on said shaft for counter-balancing said gyrating connections, rows of coil springs disposed lengthwise in independently mounted relation between said live frame and said stationary frame and on opposite sides of said shaft, whereby the end portions of said live frame are yieldingly supported in both horizontal and vertical directions, and abutment elements applied to said frames, respectively, for receiving the springs individually therebetween and in a position at substantially right angles to the screening surface of the live frame, the upper ends of said springs acting on said live frame on a longitudinal line substantially intersecting the axis of said shaft.

WILLIAM LOUIS WETTLAUFER.
